UNITED STATES PATENT OFFICE.

STEPHEN M. PALMER, OF TONICA, ILLINOIS.

OVERSHOE-RETAINER.

1,089,073.

Specification of Letters Patent.

Patented Mar. 3, 1914.

Application filed May 14, 1913. Serial No. 767,746.

To all whom it may concern:

Be it known that I, STEPHEN M. PALMER, a citizen of the United States, residing at Tonica, in the county of La Salle and State of Illinois, have invented certain new and useful Improvements in Overshoe-Retainers, of which the following is a specification, reference being had to the accompanying drawings.

10 This invention relates to new and useful improvements in buckleless rubber or overshoe retainers, the object of the invention being to provide a retainer which is formed of a single length of wire and adapted to engage the heel of the rubber to hold the same securely in position when placed upon the foot of the wearer, said retainer being securely held in position by means of a lace which is secured to the retainer upon each 15 side of the shoe and the ends thereof tied together over the instep of the foot.

Another object of the invention is to provide a retainer of the above character which will possess advantages in points of efficiency and durability, is inexpensive of manufacture and at the same time is simple in construction and operation.

With the above and other objects in view, this invention consists in the novel features 20 of construction and the combination and arrangement of parts to be hereinafter more fully described, pointed out in the claims and shown in the accompanying drawings, in which—

35 Figure 1 is a detail perspective view of an overshoe illustrating the application of my improved retainer; Fig. 2 is a detail perspective view of the retainer member; and Fig. 3 is a similar view illustrating the 40 same in its folded position.

In carrying out my invention, I provide a single length of pliable wire, one end of which is bent to form an elongated loop 1, the other end of the wire being then bent to 45 further form a curved U-shaped member 2, which is adapted to engage around the heel of the overshoe. After the U-shaped member 2 has been formed, the end of the wire is twisted, as shown at 3, and then bent to 50 form the elongated loop 4, the wire after forming the loop 4 being engaged with the twisted portion 3 and then bent to form the U-shaped stirrup 5 which is adapted to engage beneath the foot in front of the heel of 55 the overshoe. It will be apparent that my improved fastener may be formed from a

ring which comprises a single length of wire by so shaping the ring that it will provide the loops 1 and 4 and by twisting portions of the ring, to form the U-shaped members 60 2 and 5 which engage the heel and the bottom of the foot and front of the heel.

In applying my improved device to the foot of the wearer, the overshoe is first placed in position upon the foot and the 65 stirrup 5 engaged beneath the bottom of the overshoe in front of the heel portion thereof. The U-shaped portion 2 is then engaged with the rear of the heel of the overshoe and the retainer is securely held in position by 70 means of the shoe string 6, the ends of which are passed through the loops 1 and 4 and tied over the instep of the foot, as shown at 7. It will be readily apparent that the extreme end of the wire, after forming the U- 75 shaped member 5, is engaged with the twisted portion of the first end, as shown at 8.

From the above it will be readily apparent that I have provided a simple and durable overshoe retainer which, if constructed 80 of a suitable pliable wire, may be quickly and readily folded together, as illustrated in Fig. 3 and placed in the pocket or in the toe of the overshoe when not in use. It will also be apparent that the device may be 85 quickly and readily unfolded and applied to the overshoe when it is desired to use the same, the same being securely held in position by means of the shoe string 6, as illustrated in Fig. 1. It will be readily apparent that any suitable means may be used for connecting the loops 1 and 4 in place of the string 6. It will be readily apparent that when the device is ready for use, the member 5 will be disposed at right angles to the 90 member 2 so that the same may be quickly and readily applied to the heel of the overshoe. From the above description it will be readily apparent that I have provided a simple and durable device of the class described which can be manufactured at a comparatively low cost.

While I have shown and described the preferred form of my invention, it will be obvious that various changes in the details 105 of construction and in the proportions may be resorted to for successfully carrying my invention into practice, without sacrificing any of the novel features or departing from the scope of the appended claims.

What I claim is:—

1. A device of the class described includ-

ing a single length of wire bent to form U-shaped members disposed at right angles to each other, and elongated loops formed in the wire at the junction of the two U-shaped members and a detachable connection between said loops.

2. A device of the class described including a single length of wire, one end of which is bent to form an elongated loop, said wire being thence bent to form a curved U-shaped member, and thence bent to form a second loop arranged in spaced relation with the first with a portion of wire between each loop and said U-shaped member, said wire

being thence bent to form a second U-shaped member disposed at right angles to the first U-shaped portion and its extreme end being twisted upon the portion between the first loop and the first U-shaped member, and flexible connecting means between said loops, as and for the purpose set forth.

In testimony whereof I hereunto affix my signature in the presence of two witnesses.

STEPHEN M. PALMER.
